OUTDOOR LIGHTING FIXTURE

William S. Akely and Ernest P. Kochale, Jr., Oak Park, Ill., assignors to Guardian Light Company, Oak Park, Ill., a corporation of Illinois

Application May 2, 1957, Serial No. 45,977

Term of patent 14 years

(Cl. D48—23)

FIG. 1

FIG. 2

Fig. 1 is a top plan view of an outdoor lighting fixture showing our new design;

Fig. 2 is a perspective view showing the bottom and one end of the fixture;

Fig. 3 is a perspective view taken from the opposite end of the fixture; and

Fig. 4 is an enlarged sectional view taken along lines 4-4 of Fig. 1 with the internal details omitted for convenience of illustration.

We claim:

The ornamental design for an outdoor lighting fixture, substantially as shown.
